UNITED STATES PATENT OFFICE.

EMILE WALDMEIER, OF GULFPORT, MISSISSIPPI.

AUTOMATIC ATOMIZER FOR INTERNAL-COMBUSTION ENGINES.

1,227,225.

Specification of Letters Patent. Patented May 22, 1917.

Application filed June 16, 1916. Serial No. 104,006.

To all whom it may concern:

Be it known that I, EMILE WALDMEIER, a citizen of the United States, and a resident of Gulfport, in the county of Harrison and State of Mississippi, have invented a certain new and useful Improvement in Automatic Atomizers for Internal-Combustion Engines, of which the following is a specification.

10 My invention relates to improvements in devices for injecting water in an atomized state into an internal combustion engine, and it consists in the combinations, constructions, and arrangements herein described and claimed.

An object of my invention is to provide a simple device, by means of which the water from the water jacket of the engine may be automatically drawn into the intake manifold of an internal combustion engine, thereby mixing with the fuel and air, to cool the engine and to reduce the deposit of carbon in the cylinders.

20 A further object of my invention is to provide a device which may be readily attached to the intake manifold of any internal combustion engine, and which will thereafter work automatically to effect the injection of the atomized water.

25 Other objects and advantages will appear in the following specification, and the novel features of the invention will be particularly pointed out in the appended claims.

My invention is illustrated in the accompanying drawings, forming part of this application, in which:

Figure 1 is a side view showing my device applied to an engine.

Fig. 2 is a section along the line 2--2 of Fig. 1.

Fig. 3 is a section along the line 3--3 of Fig. 2.

Fig. 4 is a perspective view of the valve.

In carrying out my invention, I provide a body portion 1 which is hollow and which has at one end a threaded extension 2, this extension being arranged to enter a threaded bore 3^a in the intake manifold 3.

At the opposite end of the hollow body portion 1 is a hinged plate 4 which has small perforations 5. The plate is hinged to the body portion at 5^a in such a manner that it is free to move toward and away from the body portion, in the manner herein-after explained.

At 6 I have shown an extension of the

body portion 1, which constitutes in fact a valve casing. This casing contains a valve 7, whose valve stem 7^a projects into the interior of the body portion 1. The valve 7 is normally retained on its seat by means of a spring 8, the tension of the spring being regulated by a screw plug 9.

A threaded cap 10 is carried by the body portion 1. This cap is provided with a series of openings 10^a. The cap bears a revoluble plate 11 having openings 11^a arranged to register with the openings 10^a in the cap 10. A thumb screw 12 is used to lock the plate 11 in its adjusted position.

The valve casing 6 may be put into communication with the interior of the water jacket of one of the cylinders 13, by means of a pipe 14, see Fig. 1, a union 15, securing the pipe to the valve casing.

From the foregoing description of the various parts of the device, the operation thereof may be readily understood.

Normally the position of the plate 4 is that shown in dotted lines in Fig. 2. This plate 4, it will be observed, has an arm 17 on its inner face, the end of the arm being arranged to engage the end of the valve stem 7^a when the plate is drawn inwardly. The arm 17 has weight enough to cause the plate 4 to assume the dotted line position as stated.

Normally the valve 7 is against its seat, so as to shut off any flow of water from the water jacket through the pipe 14. Now when the engine is started up, the suction in the cylinders will cause the plate 4 to be moved from the dotted line position to the full line position shown in Fig. 2, the arm 17 will engage the end of the valve stem 7^a, thus unseating the valve 7 and permitting a flow of water from the water jacket through the pipe 14, and into the interior of the body portion 1. Air is also drawn through the aligned openings 11^a and 10^a, and through the perforations 5. This air will cause the water to be blown into the intake manifold, and the fine streams of air through the openings 5 will atomize the water. In order to further atomize the water I provide a screen 18 so that when the water finally passes into the interior of the intake manifold 3 it is in the form of mist or vapor. This is carried into the interior of the cylinders, and tends to cool the latter, as well as to prevent the deposit of carbon. As soon as the engine stops working, the plate 4 drops back and

the valve 7 is seated against its seat, being held there by the spring 8 so that the flow of water is now cut off.

I am aware that it is broadly old to inject water into the intake manifold of internal combustion engines. Such is not my invention. My invention comprises a device in which the water from the water jacket may be atomized by means of a cool stream of air and blown with the air into the intake manifold, thus arriving in the cylinders at a lower temperature than where the steam, for instance, from the water jacket is admitted directly to the intake manifold and does not come in contact with the air. The invention further lies in the provision of means for automatically controlling the valve which admits water into the intake manifold by the air itself.

10 I claim:

1. An automatic atomizing device for internal combustion engines comprising a hollow casing, means for attaching said casing to the intake manifold and to establish communication between the intake manifold and the interior of the casing, a valve casing communicating with said main casing and carried thereby, a valve within the valve casing, means including a pipe for establishing communication between said valve casing and the water jacket of the engine, means carried by said main casing and movable in response to the suction of the cylinders for

opening said valve, said last named means comprising a perforated hinged plate, an arm carried by said hinged plate and arranged to extend within said casing, said arm being adapted to engage the valve stem for shifting the valve, a perforated cap covering said hinged plate, and means for regulating the amount of air entering said perforated cap.

2. An automatic atomizing device for internal combustion engines, comprising a hollow casing, means for attaching said casing to the intake manifold and to establish communication between the intake manifold and the interior of the casing, a valve casing communicating with said main casing and carried thereby, a valve within the valve casing, means including a pipe for establishing communication between said valve casing and the water jacket of the engine, means carried by said main casing and movable in response to the suction of the cylinders for opening said valve, said last named means comprising a perforated hinged plate, an arm carried by said hinged plate and arranged to extend within said casing, said arm being adapted to engage the valve stem for shifting the valve, a perforated cap covering said hinged plate, and a rotatable perforated plate carried by said cap for regulating the amount of air entering the cap.

EMILE WALDMEIER.
